UNITED STATES PATENT OFFICE.

JOHN J. DONOVAN, OF OAKLAND, CALIFORNIA.

DESK ARRANGEMENT.

1,300,934.

Specification of Letters Patent. Patented Apr. 15, 1919.

Application filed December 12, 1918. Serial No. 266,403.

To all whom it may concern:

Be it known that I, JOHN J. DONOVAN, a citizen of the United States, residing at Oakland, in the county of Alameda and State of California, have invented new and useful Improvements in Desk Arrangements, of which the following is a specification.

This invention relates to school furniture, and particularly to a desk construction which permits a novel seating arrangement within the class rooms.

To obtain the best possible lighting and hygienic conditions when constructing school buildings, and particularly when laying out the class rooms, it is required that about 60% of the exterior wall surface shall be allowed for the transmission of daylight. The windows thus provided are generally placed along the outer wall, and, as the desks and aisles generally run parallel with the outer wall, it can readily be seen that the pupils occupying the rows nearest the windows are exposed to excessive light, and, as the light, practically speaking, enters at right angles to the line of vision, it has been found that it is more or less injurious to the eye-sight, as a considerable amount of light penetrates the corners of the eyes of the pupils when they are studying and also when sitting in an erect position.

Furthermore, the pupils seated in these rows from the center to the rear are particularly affected because of the great amount of glass area positioned to the left and in front of them. This is still more pronounced when the windows extend to the front wall of the room, which is often the case where the rooms are short in length in order to provide the required amount of light for the room. Practically two-thirds of the pupils would, in that case, be affected. Again, where the desks are arranged in parallel rows with the teacher's desk at the front, and almost always in the center position, it is necessary for the pupils in the outer rows, when giving their attention to the teacher, either to turn the head or the body to give the proper attention. Two obvious defects are thus apparent, first, improper positioning with relation to the rays of light entering the room, and, secondly, improper positioning of the pupils in the outer rows when giving their attention to the teacher.

One of the objects of the present invention is to provide a desk and seat which are

so constructed that the above defects will be obviated, said desk and seat being adapted to be positioned on an angle with relation to the row formation of the desks and 60 still maintain the row formation, thus permitting the pupils in the outer rows to give the teacher their attention without turning the head or body and also permitting the pupils in the rows nearest the windows 65 to be exposed to all the light required without affecting their eye-sight. Another object of the invention is to provide a desk of rhomboidal form, said desks having their ends parallel with the aisle and the corners 70 rounded to prevent danger or injury to the teacher and pupils when using the aisles.

The invention consists of the parts and the construction, combination and arrangement of parts hereinafter more fully described 75 and claimed, having reference to the accompanying drawings, in which—

Figure 1 is a plan view of a school room in which the desks are constructed and arranged according to my invention. 80

Fig. 2 is a plan view of a series of desks and seats.

Fig. 3 is a side elevation of a desk and seat.

Referring to the drawings in detail, A indicates a base member of suitable construction on which is formed or otherwise secured a pair of pedestals 2 and 3, the pedestal 2 being provided for the support of the desk indicated at 4 and the pedestal 3 for the 90 support of the seat shown at 5.

The formation of the desk proper, and particularly the top thereof, is one of the important features of the present invention. By referring to Fig. 2, it will be seen that 95 the desk top is rhomboidal in form and that the seat 5 employed in connection therewith is so positioned that its longitudinal axis is arranged substantially at right angles to the longer side of the rhomboid, and that 100 the ends 7 of the desk top are parallel with the aisle.

It can therefore be seen that each pupil in the row will face the teacher without turning the head or body and also that the light 105 entering through the windows will not have a tendency to excessively penetrate the corners of the eyes, as the light rays are, practically speaking, entering the room over the pupil's left-hand shoulder. Again, these 110 advantageous features are obtained without disturbing the parallel aisle and row forma-

tions and without subjecting the teacher or pupils to danger when using the aisles, as the ends of the desks are parallel with the aisles and the corners are rounded, as shown.

- 5 From the foregoing, it will be noted that very much less direct light will enter the eyes of the pupils seated at this form of desk when studying and when the head is in an erect position with the eyes directed to the 10 front of the room or to the teacher. This will have an important bearing on preserving the general health and the eye-sight of the pupils. Furthermore, the position of the pupil will be more natural, and, consequently, more comfortable, as a greater portion 15 of the hours of class room work is employed in giving attention to the teacher. Another advantage will be less strain on the eyes when reading written matter or looking at illustrated matter whether placed on a desk or a blackboard in the front of the room. A further advantage lies in the possibility of placing the teacher's desk closer to the wall opposite the windows so that the 20 25 third and fourth rows of desks could also be rhomboidal in form. This should materially increase the number of pupils aided favorably. Advantages could also be extended to lessening the cost in construction 30 of the building and in simplifying the planning and design. At the present time it is considered necessary to provide a solid wall at the front and right of the desks so that daylight is obstructed from entering at this 35 angle. This requires juggling of the exterior surface and interior areas and often adds small rooms at the ends of the building in order to obtain symmetry in the exterior design.
- 40 While the drawings show rhomboidal desks in the outer two rows nearest the windows, it is obvious that they may be employed in as many rows desired or wherever desired. Again, by referring to Fig. 2 it 45 will be seen that the acute angle of the

rhombus is marked 14°. This may, however, be varied to suit existing conditions.

I also wish it understood that while a specific form of desk and seat support is here shown, it should be obvious that this 50 may be changed; similarly, that the materials and finish of the several parts may be such as the experience and judgment of the manufacturer may dictate.

Having thus described my invention, what 55 I claim and desire to secure by Letters Patent is:

1. The combination of a plurality of rows of desks with intermediate aisles, each desk with its individual seat, the locus of the 60 ends of any row of desks lying in a substantially right line parallel with the aisle, a seat arrangement for each desk with the longitudinal axis of the seat substantially at right angles to the back of its particular 65 desk.

2. A desk adapted to be arranged in row formation, said desk being disposed on an angle with relation to the row formation but having its ends parallel with the line of 70 row formation, and a seat for each desk in the row, said seat having its longitudinal axis substantially at right angles to the longer side of the desk.

3. In school furniture, the combination of 75 a desk and a seat, said desk and seat adapted to be arranged in lineal row formation, said desk having a top of rhomboidal form and having its ends parallel with the linear row 80 formation, and said seat having its longitudinal axis substantially at right angles to the longer side of the rhomboid.

In testimony whereof I have hereunto set my hand in the presence of two subscribing witnesses.

JOHN J. DONOVAN
